UNITED STATES PATENT OFFICE.

THEODORE J. SPICKERMAN, OF MCKEESPORT, PENNSYLVANIA.

TIE AND RAIL-FASTENER.

1,006,309.

Specification of Letters Patent. Patented Oct. 17, 1911.

Application filed July 24, 1911. Serial No. 640,289.

To all whom it may concern:

Be it known that I, THEODORE J. SPICKERMAN, a citizen of the United States of America, residing at McKeesport, in the county 5 of Allegheny and State of Pennsylvania, have invented certain new and useful Improvements in Ties and Rail-Fasteners, of which the following is a specification, reference being had therein to the accompanying 10 drawing.

This invention relates to ties and rail fasteners, and the primary object of my invention is to substitute concrete, iron or steel for wood in providing a railroad tie, where- 15 by the use of the tie will be considerably lengthened and a more durable structure provided.

Another object of this invention is to provide a tie possessing sufficient strength 20 and firmness to support the great weight of rolling stock that passes over the same.

A further object of this invention is to furnish a tie with a novel fastener that will prevent lateral and vertical displacement 25 of rails mounted upon the tie.

A still further object of this invention is to accomplish the above results by a mechanical construction that will preserve the alinement of rails and compensate for the expansion 30 and contraction of the same.

These and such other objects as may hereinafter appear are attained by a combination 35 of structural elements that will be hereinafter specifically described and then claimed.

Reference will now be had to the drawing, where:

Figure 1 is a longitudinal sectional view of a portion of a tie in accordance with this invention, Fig. 2 is a similar view illustrating a modification of the invention, Fig. 3 40 is a plan of the same, Fig. 4 is a perspective view of the fastener applied to a tie of the channel or I-beam type, Fig. 5 is a similar view of a detached nut locking device, Fig. 45 6 is a similar view of a detached shoe, Fig. 7 is an elevation of a modified form of fastener, and Fig. 8 is a cross sectional view of a tie of the I-beam construction provided with another modified form of fastener.

50 The reference numeral 1 denotes a concrete tie having the same proportions as the present type of wooden tie. The tie 1, adjacent to each end thereof, is provided with pockets 2 and during the formation of 55 the concrete tie, a metallic casing 3 is embedded in the pockets 2. The pockets 2 are

approximately one-half the width and depth of the tie, and the end walls of the casing are provided with webs 4 and a top plate 5 corresponding in width to said casing. The 60 webs 4 extend into the body of the tie and firmly anchor the casing within the pockets 2. The top plate 5 is of a greater length than the webs 4 and is countersunk in the upper surface of the tie, with the outer ends 65 thereof bent downwardly, as at 6 to engage in the body of the tie. The top plate 5 between the pockets 2 is adapted to support the base flanges 12 of a rail 13 and extends over a portion of the pockets.

The longitudinal walls of the casing 3, at the upper edges thereof, are connected by retaining members or shoes 8 having the under surface thereof rounded, as at 9. The shoes 8 are integral with the side walls of the casing and also with the plate 5. The members are adapted to close the openings of the casing 3, with the exception of diametrically opposed openings 10 and 11.

Adapted to hold the base flanges 12 are the 80 hook-shaped ends 14 of curved bolts 15, said bolts having the opposite ends thereof screw threaded, as at 16 and extending upwardly through the openings 10.

Mounted upon the hook-shaped ends 14 of the bolts 15, between the flanges 12 and the hook-shaped ends 14, are the slotted ends of resilient nut locking devices 17, said devices being slotted, as at 18 to provide clearance for the hook-shaped end of each bolt. The 90 outer ends of the devices are punched and sheared to provide openings 19, the punched and sheared material being bent outwardly to provide flanges 20 adapted to engage the facets of a nut 21 screwed upon the threaded 95 end 16 of each bolt. The nut 21 is adapted to retain the bolt in position and the flanges 20 are adapted to retain the nut upon the bolt, whereby vibrations of the fastener cannot displace the nuts.

In Figs. 2 and 3 of the drawing there is illustrated a modification of the invention, wherein the tie 22 has a single pocket 23, adjacent to the end thereof, for a single casing, and a modified form of nut locking device is used, which comprises a washer 24 having one edge thereof engaging the outer base flange of the rail 13 and the opposite edge thereof provided with a lug 25 which is bent upwardly to engage the facet of a 110 nut 26 screwed upon the threaded end of the bolt.

In lieu of making one of the ends of the bolt hook-shaped, both ends of a bolt 30 can be threaded, as illustrated in Fig. 7 and nuts and washers mounted upon the ends of the bolt to engage the base flanges of the rail.

In Figs. 4 and 8 there is illustrated a modification of the invention, wherein a tie of the I-beam construction is employed, the tie being designated 27 and having the top flanges 28 thereof provided with openings 29. These openings are adapted to receive the ends of bolts 31 similar to the bolts 15, and interposed between said bolts and the under sides of the flanges 28 are shoes 32 very similar to the retaining members 8 of the preferred form of construction.

In Fig. 8 the fastener consists of hook-shaped bolts 33 having the lower threaded ends provided with nuts 34.

From the foregoing it will be observed that I have devised a tie having the requisite bearing surface for the support of rails, and that the surface affords a sure and ready

means for embedding the casings, which constitute chairs for firmly supporting the rails. The rails can be easily installed by unskilled labor and can be readily tamped in a road-bed.

What I claim is:—

The combination with rails, of a concrete tie, casings embedded in said tie and having the end walls thereof provided with webs and plates adapted to anchor said casings in said tie, curved bolts arranged within said casings and having hook-shaped ends adapted to engage the flanges of rails mounted on said tie, and means including nuts mounted upon the opposite ends of said bolts and adapted to retain said bolts in engagement with said rails.

In testimony whereof I affix my signature in the presence of two witnesses.

THEODORE J. SPICKERMAN.
